UNITED STATES PATENT OFFICE.

ZAVERIO C. BIANCHI, OF SAN JOSE, CALIFORNIA.

CHALKING DEVICE FOR BILLIARD-TABLES.

1,270,775.

Specification of Letters Patent.

Patented July 2, 1918.

Application filed December 20, 1917. Serial No. 208,082.

To all whom it may concern:

Be it known that I, ZAVERIO C. BIANCHI, a citizen of the United States, residing at San Jose, in the county of Santa Clara and 5 State of California, have invented certain new and useful Improvements in Chalking Devices for Billiard-Tables, of which the following is a specification.

My invention relates to improvement in a 10 chalking device for billiard tables, and the objects of my device are:

First; to provide a chalking device for billiard tables that will prevent the wasting of chalk.

15 Second; to provide a chalking device that will bring the chalk holder over the billiard table within reach of the hand.

Third; to provide a chalking device that 20 will operate over a plurality of billiard tables in line.

Fourth; to provide a chalking device that 25 will operate over a plurality of billiard tables, one chalk holder not interfering with the operation of the other chalk holder.

Fifth; to provide a chalking device that 30 will at all times return the chalk holder to its original position after the chalk has been used.

Other objects and advantageous features 35 of the invention will be fully understood from the following description and claims when the same are read in connection with the drawings, accompanying and forming part of this specification, in which:

35 Figure 1 is a plan view of the spool frame and spool frame casing with springs and spools in position.

Fig. 2 is a front view of Fig. 1.

40 Fig. 3 is a plan view of the outside casing of my device.

Fig. 4 is a side view of the outside casing of my device, showing the tension adjustment in place.

45 Fig. 5 is a side view of one of the spring spools, showing spring attached.

Fig. 6 is an enlarged side view of the chalk holder with chalk and spring in position.

Fig. 7 is a bottom view of Fig. 6.

50 Fig. 8 is a detail view of tension adjustment attached to the outside casing of the spring spool frame.

Fig. 9 is a side view of my device in position over the billiard tables.

Like numerals of reference indicate the 55 same parts throughout the figures, in which:

1 indicates the spring spool frame; 2 are

the bolts that fasten the spool frame 2 to the ceiling 19; 3 are the spring spools; 4 is the bolt on which the spring spools 3 operate, each spring spool 3 having a steel spring as 5, one end thereof being fastened to the inner side of spool 3 at 6, and the other end thereof being fastened to bolt 4 at 7, as shown in Fig. 5; a metal bar 8 is shown fastened in any suitable manner across the inner hollow portion 9 of spools 3 for the purpose of holding spring 5 in place in the hollow portion 9 of spools 3.

The outside casing of my device is shown at 10 in Figs. 3 and 4, the same being convex 70 on the outside and concave on the inside and is made of metal of the required thickness, having a band flange 11 at its upper end with an offset groove 12 cut therein, adapted to connect casing 10 with spool frame 1 by 75 pin 13 fastened to casing 1, as shown in Fig. 2. Connected to casing 10 by rivets 14 are shown tension adjustments 15, one on each side thereof, for the purpose of operating a plurality of chalk holders in opposite directions, the upper portion thereof being adjustable up and down by bolts 16. Extended wire rope 17 is shown placed on an incline from the ceiling, as shown in Fig. 9 in either direction and held in place by a plurality of 80 pulley hangers 18 of different lengths, fastened to the ceiling 19 over the billiard tables by bolts 20, pulleys 21 are shown connected to hangers 18 over which wire rope 17 passes. On wire rope 17 is shown a stop 90 bar 22; pull-down pulleys are shown at 23 resting on wire rope 17; attached to said pulley frames 24 is cord 25; attached to the lower end of cord 25 is chalk holder 26 by rings 26^a; these chalk holders 26 are made 95 of metal and are positioned near the end of a plurality of billiard tables 27.

A spring is shown at 28 in chalk holder 26; chalk is shown in chalk holder 26 at 29, the chalk being held in chalk holder 26 by 100 flange 30 and cap 31 and is fed down by spring 28, cap 31 being machine threaded into chalk holder 26.

The operation of my chalking device for billiard tables, is as follows:

Wire rope 17 is fastened to and wound around the spring spools 3, one for each direction, as to the number of billiard tables to operate over, then wire rope 17 is drawn through the underside of pull-down pulleys 110 23, and over pulleys 21 to chalk holder 26, where the same is fastened to chalk holder

ring 26^a; a stop is fastened to extended wire rope 17 at 22 for the purpose of preventing wire rope 17 from being drawn any farther back into casing 10 by springs 5; tension adjustment is shown at 15, through which wire rope 17 passes this tension adjustment 15, is regulated by bolts 16 to any required tension on wire rope 17; when cords 25 and 17 are pulled down to use the chalk 29 in chalk holder 26, wire rope 17 is drawn out from casing 10 through tension adjustment 15, and when released the tension adjustment 15 being so adjusted as to return wire rope 17 and pull down pulleys to their original positions at the speed required; wire rope 17 being placed on an incline from the ceiling is for the purpose of returning pulleys 23 to their original positions near pulleys 21; chalk 29 is replenished in chalk holder 26 by removing cap 31 and spring 28.

Having thus described my invention, what I claim as new and desire to secure by Letters Patent, is:

1. In a chalking device for billiard tables 25 the combination of a spool frame, an engaging pin fastened to the spool frame, spools having a hollow portion therein positioned in the spool frame, a steel spring positioned in the hollow portion of each spool, a metal 30 bar, adapted to retain the steel spring in position in the hollow portion of each spool, a metal outside casing being convex on the outside, and concave on the inside thereof; a band flange at the upper end of the metal 35 casing, an offset groove in the band flange, adapted to engage the engaging pin in the

spool frame with the offset groove in the band flange, as and for the purpose described.

2. In a chalking device for billiard tables 40 the combination of a spool frame, an engaging pin fastened to the spool frame, spools having a hollow portion therein, a steel spring positioned in the hollow portion of each spool, a metal bar, adapted to retain 45 the steel spring in position in the hollow portion of each spool, a metal outside casing, tension adjustments fastened one on each side of the metal outside casing, a wire rope placed on an incline, a plurality of pulley 50 hangers of different lengths on which the wire rope rests and is operated; a stop bar, fastened to the wire rope, adapted to prevent the wire rope from being drawn back in the casing by the spring beyond a predetermined point, pull-down pulleys, pull-down pulley frames, a cord attached to each pull-down pulley frame, a metal chalk holder attached to the lower end of the cord, adapted to hold the chalk, means by which the 55 chalk is held in the chalk holder, a spring, adapted to feed the chalk down positioned in the chalk holder, as and for the purpose described.

In testimony whereof I have hereunto af-
fixed my signature this 14 day of December,
1917, in the presence of two witnesses.

ZAVERIO C. BIANCHI.
